UNITED STATES PATENT OFFICE.

SAMUEL MAJOR BEAHR, OF CINCINNATI, OHIO.

DESIGN FOR A BADGE.

SPECIFICATION forming part of Design No. 33,236, dated September 25, 1900.

Application filed July 30, 1900. Serial No. 25,355. Term of patent 3½ years.

To all whom it may concern:

Be it known that I, SAMUEL MAJOR BEAHR, a citizen of the United States, residing at Cincinnati, in the county of Hamilton and

5 State of Ohio, have invented and produced a certain new and original Design for Badges, of which the following is a specification.

In the drawings, Figure 1 is a front elevation, and Fig. 2 a perspective view, of my de-
10 sign.

The design consists of the disk or button

A as a background, with the representation of a factory B mounted thereon, and having the wheel or disk C covering a portion of its face.

I claim as my invention—

15 The design for a badge substantially as herein shown and described.

S. MAJOR BEAHR.
